UNITED STATES PATENT OFFICE

2,129,050

MULTIPLE POURING DEVICE

Maxwell G. Dumas and William S. Orr, Pittsburgh, Pa., assignors to Dumas Engineering Company, Youngstown, Ohio, a corporation of Ohio

Application October 23, 1935, Serial No. 46,320

4 Claims. (Cl. 22—79)

This invention relates to new and useful improvements in multiple pouring devices for ingot molds, and it is among the objects thereof to provide apparatus for simultaneously pouring regulable multiple streams of molten metal to a plurality of ingot molds.

Another object of the invention is the provision of a multiple pouring device which shall be movable with reference to rows of ingot molds into two or more of which the molten metal is poured simultaneously, and which shall be provided with manual controls for regulating the volume of the flow streams to the several molds into which the metal is simultaneously poured.

Still another object of the invention is to provide multiple pouring devices with mechanically operated tilting and tipping mechanism for controlling multiple flow streams and in which the flow control mechanism is adapted to provide speedy and positive adjustments of the volume of the several flow streams.

A further object of the invention is the provision of means whereby the multiple pouring device is adapted to the pouring of large or small ingots in molds having different center distances.

These and other objects of the invention will become more apparent from a consideration of the accompanying drawings constituting a part hereof in which like reference characters designate like parts and in which:

Fig. 1 is a side elevational view partially in section of a multiple pouring device embodying the principles of this invention;

Fig. 2 a front elevational view thereof;

Fig. 3 a plan view of one-half of the device shown in Figs. 1 and 2;

Fig. 4 a side elevation partially in section of a modified form of pouring device;

Fig. 5 a plan view of the structure shown in Fig. 4;

Fig. 6 a view diagrammatically illustrating the relation of the pouring receptacle and flow troughs;

Fig. 7 a front elevation diagrammatically illustrating the pouring receptacle, flow troughs and ingot molds;

Fig. 8 a side elevation partially in section of a form of multiple pouring device whereby four ingots may be poured simultaneously;

Fig. 9 a front elevational view partially in section of a modified form of the pouring receptacle shown in Fig. 8 with flow troughs and ingot molds; and Fig. 10 a plan view of the apparatus shown in Fig. 9.

With reference to Figs. 1 to 3 inclusive of the

drawings, the structure therein illustrated consists of a concrete base 1 provided with a pit for receiving ingot molds 2, the pit having shoulders 3. The base 1 is provided with tracks 4 upon which a steel frame, constructed of channels and plates 5 is mounted on wheels 6 that ride on the rails to render the sub-structure of the pouring device movable. A cross-frame 7 is supported on the wheel frames 5 and a ball-joint 8 is mounted in the cross-frame 7. A pair of longitudinally spaced flow troughs 9 are rigidly mounted on the frame, a feeding orifice 10 being provided at the bottom of the flow troughs. There are two troughs 9 to which metal is supplied through the orifice 11 of a single pouring ladle 12, the view of Fig. 3 being a plan view of one-half of the pouring device. The ladle 12 is provided with brackets 13, Fig. 3, having spherical seats that rest upon dumbbell-shaped bearings 14, Fig. 1, one end of which is supported on levers 15, 20 which are pivoted at 16, Fig. 3, and connected to cranks 17.

The front end of the ladle 12 is provided with a spherical shaped bearing bracket 18 that rests upon the spherical ball-joint 8. Levers 15 are connected to the cranks 17 by a link 19 and the cranks 17 are connected by shafts 20 through reduction gears 21 and a worm and worm gear 22 are driven by a motor 23, the gear being housed in a metal box which may be referred to and designated as a transmission 24.

Motor 23 is controlled by a switch or lever 25 and the wheel axles 6 are driven by a motor 26 controlled by a lever 27, the traversing motor 26 being provided with a brake 26a that is operated by a foot pedal 27a.

A plurality of contact brushes 28 are mounted on cross-arm support 29, attached to the frame structure to make contact with rails 30, supplying current for the motors 23 and 26.

Referring to Fig. 1, metal is supplied to the pouring ladle 12 from a ladle 31 which receives the molten metal from a melting furnace, ladle 31 being provided with a pouring orifice 32 having the usual stopper for controlling the flow.

As shown in Fig. 2, the parts, with the exception of the traversing motor and its controls, are duplicated, there being two flow openings 11 and 11a for the pouring ladle 12 into stationary flow spouts 9 and 9a.

The operation of the apparatus shown in Figs. 1 to 3 inclusive is briefly as follows: with the pouring ladle 12 in its normal position, as shown in cross-section, in Fig. 1 of the drawings, it rests upon the front central ball-joint 8 and the two

horizontally spaced dumbbell-joints 14. One of the dumbbell-joints 14 is permanently fixed in the end of lever 15 and the other fits into a socket in lever 15a and into the bracket 13 to provide for misalignment in moving the ladle. The metal is caused to flow from the main ladle 31 through the spout 32 into the pouring ladle 12 with the ingot molds 2 lined up below the stationary flow spouts 9 and 9a. The operator manipulates control levers 25 and 25a which energize the motors 23, which, in turn, actuate cranks 17 and 17a which, through links 19, pull the bell crank levers 15 forward. Movement of levers 15 raise the pouring receptacle 12, causing it to tilt about its front central ball-joint 8 and molten metal will flow from the openings 11 and 11a. The flow from the openings 11 and 11a is regulated by tipping the pouring receptacle 12 about its central ball-joint 8 and joints 14, this being accomplished by the controls 25 and 25a to raise the lever 15 or 15a as the case may be. In Fig. 3, which is a half plan view of the device, the line x—x denotes one of the tipping axes, while the tilting axis occurs at a longitudinal line through the center of the ball-joint 8, such line being at right angles to the center line, shown in the drawings as running through the ball-joint 8.

By means of the controls 25 and 25a, the pouring receptacle 12, is in the first instance, tilted 30 to raise the rear portion thereof to regulate the volume of flow to the stationary spouts 9 and by further manipulation of the individual controls 25 and 25a, the receptacle may be tipped to obtain independent regulation of the flow through each 35 of the flow openings 11 and 11a of the pouring receptacle.

By means of the hereinabove described apparatus, a plurality of ingot molds can be poured simultaneously with positive control of the flow stream from the pouring receptacle. The pouring receptacle 12 is of such capacity that the pouring of the metal from the ladle 31 may progress at a rate independently of the rate the metal is poured into the ingot molds, since the control 40 of the flow from the pouring receptacle 12 to the ingot molds through the flow spouts 9 may be regulated independently of the flow from the supply ladle 31. This continuous pouring eliminates the necessity for stopping-off the flow from the main ladle which sometimes causes freezing or sticking of the stopper plug, and at the same time the independent regulation of flow to the ingot molds permits slow pouring of the metal to the molds 45 which is advantageous in that it eliminates splashing in the mold and is productive of uniformly dense and sound ingots. The pouring to multiple molds simultaneously permits slowing of the pouring to any desired degree which allows control or regulation of the individual streams. 50 When a pair of ingot molds have been fully teemed, the controllers 25 and 25a are manipulated to reverse the motors 23 and 23a which causes the pouring receptacle 12 to tilt back to the position where the level of the molten metal is below the flow openings 11 and 11a, thus shutting off the flow. The traversing motor 26 is then energized 55 and the entire receptacle moves on tracks 4 to position where the stationary flow spouts 9 will be centered above an empty pair of ingot molds, and the pouring operation is then repeated.

The apparatus shown and described in connection with Figs. 1 to 3 of the drawings is especially adapted for use in pouring small ingots such as alloy steel, but for use in the multiple pouring of 75 ingots with larger centers such as seven ft. ingots

for sheet metal fabrication, it would necessitate lowering one end of the pouring receptacle an excessive amount in the tipping operations, and for this reason, the form of multiple pouring apparatus shown in Figs. 4 to 7 inclusive of the drawings, 5 is preferred. This structure is slightly modified, although inherently it embodies the same principles of pouring controls described in connection with Figs. 1 to 3 of the drawings.

The structure of Figs. 4 to 7 inclusive is as follows: The numeral 101 designates the ladle by which the molten metal is supplied to the pouring device; 102 the pouring receptacle which, instead of having a central front bearing support, is provided with longitudinally spaced bearings 103 15 and 103a at the front bottom portion of the receptacle, these bearings being mounted on levers 104 which are pivoted to a cross-frame 105 at 106. The pouring receptacle 102 is open at the top so that in either its normal upright or tilted position the opening will be in alignment with the discharge opening 101a of the ladle, thus permitting continuous pouring from the ladle when the multiple pouring device is in use. The pouring receptacle 102 is supported at its rear portion by roller 25 107 that is mounted on a bell-crank 108 which is supported on a bearing 109. One end of the bell-crank 108 is connected by a link 110 to a crank 111 that is rotated through a transmission 112 driven by motor 113. Levers 104 are connected by links 30 115 and 115a to levers 116 and 116a mounted on a rock shaft 117 which is provided with a lever 118 that is connected by a link 119 to the transmission 120. Upon rotation of the rock shaft 117 in one direction, link 115 will be pulled downwardly to 35 tip one end of the pouring receptacle 102 and in the reverse direction of movement of the rock shaft, link 115a will be drawn downwardly to tip the receptacle in the opposite direction. The tipping mechanism is actuated through a transmission 120 driven by motor 121, while the tilting operation is by the transmission 112 and motor 113 as previously explained.

The rear roller support 107 for the tilting receptacle is mounted on a bracket 107a which is 45 carried by shaft 109 that in turn is actuated by the bell-crank 108. The pouring receptacle is mounted on a frame structure that is supported by wheeled axles 122 on rails 123 of the sub-structure. Ingot molds 124 are supported on 50 wheeled trucks 125 placed beneath the receptacle which is adapted to traverse the row of ingot molds for the pouring operations.

A stationary flow spout 126 is provided beneath the flow passages 127 and 127a of the pouring 55 receptacle 102. Reference numerals yy and y'y', Fig. 5, designate the tipping axes of the pouring receptacle. Numeral 127 designates the controller and numeral 128 the tipping motor, 128 the controller for the traversing motor, not shown; 60 and 129 the controller for the tilting motor 113.

The space designated by the numeral 130 is for the main ladle stopper operator. The operation of the structure shown in Figs. 4 to 7 inclusive of the drawings is briefly as follows:

With the pouring ladle in the position shown in Fig. 4 and a plurality of ingot molds lined up beneath the stationary spouts 126 and 126a, the tilting motor 113 is energized by the controller 129 which, through operating mechanism 70 112, 111, 110, 109, 108 and 107a, causes roller support 107 to raise the rear portion of the pouring receptacle 102, thereby tilting it on the fulcrum supports 103 and 103a. When it is desirable or necessary to tip the receptacle 102, about 75

either axes yy or $y'y'$, the controller 127 is manipulated to energize the tipping motor 121 in either direction of rotation, depending upon which axes, yy or $y'y'$, the tilting receptacle is thereby tipped around.

In this manner, the metal flowing from the passages 127 and 127a of the pouring receptacle can be separately controlled to regulate the flow of the metal to the ingot molds. When the molds are filled, the tilting device is operated to lower the pouring receptacle by shutting off the flow from passages 127 and 127a to the flow spouts 126 and 126a. The pouring receptacle is then moved by manipulating controller 128 of the traversing motor to bring the flow spouts to center with an empty pair of ingot molds.

Fig. 6 of the drawings illustrates the use of the device when pouring large ingots and Fig. 7 for small ingots, the spacing of the ingots being such that a pair can be aligned with the flow spouts by centering the latter with the ingot molds.

The invention may also be employed to control the flow of metal for quadruple pouring by providing a plurality of openings in the flow spouts which are rendered movable to tip them as shown in Fig. 9 of the drawings. Apparatus for this purpose, with reference to Figs. 8 to 10 inclusive of the drawings, consists of a supply ladle 201 having an opening 202 above a pouring receptacle 203 which, as in the structure of Fig. 4, is provided with a pair of ball supports 204 and 204a longitudinally spaced at the front of the receptacle and a supporting roller 205 at the rear of the receptacle, the roller for tilting and the movable ball-joints for tipping being operative through the same mechanism described in connection with Fig. 4.

The tilting roller 205 is mounted on an arm 206 carried by shaft 207 that is rocked by a lever 208 operated by a crank 209 of a transmission 210 that is driven by a motor 211. The front ball supports 204 and 204a are mounted on levers 212, operated by cranks 213, carried by a rock shaft 214 which is operated by a crank 215 of a transmission 216 driven by a motor 217, the latter being designated the tipping motor. Links 218a have slotted openings 218 which engage pins 219 of the rock arm, and in one direction of rotation of rock shaft 214, the lever 212 will be actuated in the opposite direction of movement and the rock shaft lever 212a will be actuated to raise or lower the ball-seat 204 or 204a, respectively, thus tipping the pouring receptacle 203 in the manner desired to control the flow of the metal from the passage 220 or 220a to a pair of movable flow spouts 221 and 221a, each of which is provided with a pair of flow passages, the spouts 221 having passages 223 and 223a.

The flow spouts 221 are suspended by links 224, supported on levers 225, pivoted at 226, having link connections 227 with a rock arm 228, mounted on rock shaft 229, having a crank 230 connected by link 231 to a crank 232 of a transmission 233 driven by motor 234, there being a separate actuating mechanism for each of the movable flow spouts as shown in Fig. 10 of the drawings. The numeral 235 designates the trough tipping controller; numeral 236 the ladle tipping controller; 237 the ladle tilting controller; 238 the trough tipping controller; and 239 the controller for the traversing motor, not shown. The numeral 240 designates the ingot mold supported on wheel trucks 241.

The operation of the above described mecha-

nism is briefly as follows: Metal is poured from ladle 201 to the pouring receptacle 203, and the latter is tilted by manipulation of controller 237, which energizes motor 211 and raises the rear supporting roller 205, through the transmission 210 and connecting linkage. The pouring receptacle is then tipped to regulate the flow through passages 220 and 220a by manipulating the controller 236 to energize motor 217 to actuate levers 212 and 212a, through the transmission 216 and the rock shaft 214, the tipping being around the axes yy and $y'y'$, this being the same control and operating mechanism as shown in Fig. 4, excepting that the levers are connected to the rear of the apparatus. As the metal flows to the movable troughs 221, the volume of flow from the separate flow streams 222 and 222a of trough 221, and 223 and 223a of trough 221a can be regulated by the trough tipping controllers 235 and 238 which energize motors 234a and 234, respectively, which, through transmission 233a and 233, operate links 231a and 231, through which levers 225a and 225 are actuated. As the levers are moved, the troughs are tilted as shown in Fig. 9, the illustrations being greatly exaggerated for this purpose.

By this manner of control, the flow of metal from the pouring receptacle 203 through the pair of flow passages to the troughs can be regulated as desired, and the multiple streams flowing from each of the tilting troughs can be regulated as desired to simultaneously pour the metal into four ingot molds.

When the trough is perfectly level, it is supported on four supporting trunnions, which consist of brackets with a round end. Onto these round bracket ends a socket on the trough rests. When the trough is tipped, it is supported by levers 225 or 225a with the opposite ends of the trough supported by the brackets and trunnions. This gives the trough a three-point suspension, rigid enough so that it will not turn over, which would happen if it was supported on the levers 225 and 225a only.

It will be apparent from the foregoing description of the invention that multiple pouring apparatus constructed and operated in accordance therewith provides positive means for obtaining regulable multiple streams of molten metal for charging or pouring a plurality of ingot molds simultaneously. It is also apparent that the apparatus is of rugged, compact and relatively simple mechanical construction in which the operating parts are subjected to minimum wear.

Although several embodiments of the invention have been herein illustrated and described, it will be apparent to those skilled in the art that various modifications may be made in the details of construction without departing from the principles herein set forth.

We claim:

1. In a multiple pouring apparatus, a pouring receptacle having a plurality of flow outlets and flow spouts beneath said flow outlets, a three-point support for said receptacle constituting a tilting and a plurality of tipping axes, and means for raising and lowering said supports independently to selectively tilt and tip the receptacle to thereby regulate the flow of metal from the receptacle outlets to the flow spouts therebeneath.

2. In a multiple pouring apparatus, a pouring receptacle having a plurality of flow outlets and flow spouts beneath said outlets, a support for tilting and tipping said receptacle comprising a pair of pivot bearings constituting a tilting axis

- and a pivot bearing cooperating with each of said pair of bearings to constitute tipping axes for said receptacle, and means for raising and lowering said bearings to selectively tilt and/or tip said 5 receptacle to thereby regulate the flow of metal from the receptacle outlets to the flow spouts therebeneath.
3. Apparatus for pouring ingots which comprises a pouring receptacle having a pair of spaced outlets in a common horizontal plane, a pouring receptacle in cooperative alignment with each outlet of said first-named receptacle, each of said second-named receptacles having a plurality of flow outlets in a horizontal plane parallel with respect to the plane of the outlets of said first-named receptacle, said first-named receptacle having a plurality of movable supports and actuating means rendering said supports independently movable relative to each other where- 10 15 20
- 5 by the receptacle is adapted for movement about a tilting and tipping axis, and said second-named receptacles each having a plurality of vertically movable supports, and mechanism for independently actuating said supports whereby said receptacles are severally adapted to be tilted to regulate the flow of molten metal through the plurality of outlets in accordance with the desired 5 rate of flow from each of its outlets.
4. In a multiple pouring apparatus, a pouring receptacle having a plurality of flow outlets and flow spouts beneath said outlets, a ball and socket joint at the front end intermediate the outlets of 10 said receptacle, and a pair of ball and socket joints at the rear of the receptacle which, together with the first-named joint, form tilting and tipping axes, said last-named joints being supported on levers adapted for independently 15 raising said joints relative to each other to thereby tip the receptacle and to raise said joints simultaneously to thereby tilt the receptacle, and means for actuating said levers.

20

MAXWELL G. DUMAS.
WILLIAM S. ORR.
